DESIGN FOR AN OVERALL BIB

Milton D. Jacobson, Birmingham, Ala.

Application January 22, 1948, Serial No. 143,968

Term of patent 14 years

(Cl. D3—17)

To all whom it may concern:

Be it known that I, Milton D. Jacobson, a citizen of the United States and a resident of Birmingham, county of Jefferson, State of Alabama, have invented a new, original, and ornamental Design for an Overall Bib, of which the following is a specification, reference being had to the accompanying drawing, forming a part thereof.

The drawing represents the bib, showing my new design. The diagonal lines in the drawing are for showing contrasting colors only.

The essential features of my design reside in the portion shown in full lines on the drawing.

I claim:

The ornamental design for an overall bib, as shown and described.

MILTON D. JACOBSON.
